UNITED STATES PATENT OFFICE.

JOHN F. ROWLAND AND GALEN D. HULL, OF ASHEVILLE, NORTH CAROLINA.

POWDER-PUFF.

SPECIFICATION forming part of Letters Patent No. 736,786, dated August 18, 1903.

Application filed July 25, 1902. Serial No. 116,933. (No model.)

To all whom it may concern:

Be it known that we, JOHN F. ROWLAND and GALEN D. HULL, citizens of the United States, and residents of Asheville, in the county of Buncombe and State of North Carolina, have invented a new and Improved Powder-Puff, of which the following is a full, clear, and exact description.

The purpose of the invention is to provide a simple, durable, and convenient form of powder-puff especially designed to contain talcum powder, and to so construct the puff that the material may be placed in large quantities in the puff and held distributed and in such manner that the puff may be manipulated to cover large or small surfaces and so that all of the working surfaces of the puff may be utilized at all times and adapted to all parts of the human form.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a rear elevation of the improved puff, a portion being shown in section. Fig. 2 is a central longitudinal section through the puff, and Fig. 3 is a front elevation of the puff.

The body A of the puff is made of two pieces of material 10 and 11, correspondingly cut to any desired shape, that shown in the drawings being elliptical. The back piece 10 is of a fabric through which a powder will not sift—leather or a like pliable substance—and the front piece 11 is of a loosely-woven fabric having preferably a soft or downy outer surface or perforated chamois or the like. The two pieces or sections 10 and 11 of the body A are connected near their margins by a continuous line of stitching 12, although an equivalent means may be employed, and said body is divided transversely into two compartments B and B' by a central transverse line of stitching 13. These compartments are filled with powder to such a depth from front to rear that the puff may be used for some time without replenishing,

which may be done by opening the compartments at one point and again closing them after they are filled.

The auxiliary back of the puff consists of 55 a separate piece 14 of any desired material, plain or decorated, and may be of the same size as or of a larger size than the body, being secured to the body A at or near its margin by stitching or other approved means. 60 This auxiliary back is provided with a pocket C at or near the compartment B', for example, and of a size corresponding to that of said compartment. The mouth of this pocket is adjacent to the dividing-line 13, between the compartments B and B', as is shown in Fig. 2, and while the pocket is formed in the auxiliary back 14 said back is in one piece. This is accomplished by making a transverse cut 15 in the material to extend to opposite points of attachment of the auxiliary back to the body and then bending the undercut marginal portions of the auxiliary back upon itself, producing overlapping or overlaying plaits or folds 16 and 17. (Shown best in Fig. 1.) In thus folding the auxiliary back 14 the material at the outer wall of the mouth of the pocket is folded in, producing a hem 18, (shown in Fig. 2,) and the outer wall of the pocket at its mouth is carried over the body portion of the material of the auxiliary back, as is also shown in Fig. 2. By inserting the fingers in the pocket C the puff is supported by said fingers and the palm of the hand and can be readily manipulated to successfully reach any portion 80 of the body. Auxiliary to the pocket C a diagonal band D is secured to the auxiliary back 14, as is shown in Figs. 1 and 2, beneath which band all the fingers of the hand may be introduced to manipulate the puff, if desired.

It will be observed that by dividing the puff into two compartments a large quantity of powder may be placed in the puff and the powder will not be liable to sift down to one 95 end as it is used. Furthermore, the puff can be conveniently bent to adapt itself to the shape of the hand while the puff is being used and is likewise better adapted to reach various portions of the body where a puff not capable of bending could not be successfully used.

Having thus described our invention, we claim as new and desire to secure by Letters Patent—

- 5 1. A powder-puff, comprising a body having two compartments the front faces of which permit powder to sift therethrough, and provided on its back with a piece forming therewith a pocket, the mouth of which is at about the transverse center of the puff, as set forth.
- 10 2. A powder-puff, comprising a body formed of a back and a front piece secured to the back at its edges and at its center by a central transverse line of stitching forming two compartments, and an auxiliary piece on the back and forming a pocket, the mouth of which is adjacent to the dividing-line of the compartments, as set forth.
- 15 3. A powder-puff, consisting of a body formed of a front through which powder may sift, and a back composed of two pieces and to which the front is secured at its edges and

at its center to form two compartments, the outer piece of the back being provided with a transverse cut adjacent to the dividing-line of the compartments to form a pocket in the 25 back, as set forth.

4. A powder-puff, comprising a body formed of a front through which powder may sift, and a back composed of two pieces secured to the front, the outer piece of the back having 30 a transverse slit to form a pocket between the two pieces of the back at one end of the puff, as set forth.

In testimony whereof we have signed our names to this specification in the presence of 35 two subscribing witnesses.

JOHN F. ROWLAND.
GALEN D. HULL.
